(57) **CLAIM**

The ornamental design for a support base, as shown and described.

DESCRIPTION

FIG. 1 is a perspective view of a support base;
FIG. 2 is a top plan view, the bottom plan view being a mirror image;
FIG. 3 is a rear elevation view;
FIG. 4 is a side elevation view, the opposite side being a mirror image; and,
FIG. 5 is a front elevation view.
The broken lines are for environmental purposes only and form no part of the claimed design.
